UNITED STATES PATENT OFFICE.

LOUIS FRANK PONTBRIAND, OF HIGHGATE CENTER, VERMONT.

PUMP.

Application filed September 30, 1922, Serial No. 591,553. Renewed October 6, 1923.

To all whom it may concern:

Be it known that I, LOUIS FRANK PONTBRIAND, a citizen of the United States, residing at Highgate Center, in the county of 5 Franklin and State of Vermont, have invented certain new and useful Improvements in Pumps, of which the following is a specification, reference being had to the accompanying drawings.

10 This invention relates to improvements in pumps and an important object of the invention is to provide in a pump a cylinder which is capable of general application.

At the present time pump manufacturers, 15 due to the fact that some pump users insist upon a wooden suction pipe whereas others prefer a metal suction pipe, find it necessary to provide with each type of pump a pair of cylinders, one of which is adapted 20 for connection with a metallic pipe and the other of which is adapted for use in conjunction with a wooden pipe. This, of course, leads to considerable expense which it is a purpose of this invention to eliminate.

25 A further object of the invention is to provide a device of this character which is extremely simple in its construction and operation, durable in service, and a general improvement in the art.

30 These and other objects I accomplish by the construction and arrangement shown in the accompanying drawings wherein for the purpose of illustration is shown a preferred embodiment of my invention and wherein 35 like reference characters designate like parts throughout.

In the drawings:—

Figure 1 is a sectional view taken through a pump constructed in accordance with my 40 invention;

Figure 2 is a detail sectional view of the piston employed; and

45 Figures 3, 4 and 5 are detail sectional views showing different manners of engaging the suction pipe to the lower end of the cylinder;

Figure 6 is a sectional view taken through a modified form of piston.

50 Referring now more particularly to the drawings, in which a pump cylinder constructed in accordance with my invention is shown applied to a force pump standard, generally indicated at 10, the numeral 11 indicates a pipe communicating with the air chamber 12 of the pump and the numeral 13 generally designates the cylinder. The

upper end of the cylinder is provided with a threaded opening 14 for the reception of the threaded lower end of the pipe 11 and the lower end thereof is adapted for connection 60 with a suction pipe 15. In figures

I have shown this cylinder as connected with a metallic suction pipe. For this purpose the lower end of the cylinder may be provided with screw-threads 16 either 65 interiorly or exteriorly, the latter being indicated at 16'. These threads may be employed for securing to the lower end of the cylinder either a collar 17 such as illustrated in Figure 1, or a reducer coupling 70 18 such as illustrated in Figures 3 and 4. Where the flanged connection is employed, the suction pipe 15 will, of course, be provided with a second flange 19 to be bolted to the flange 17, and between these flanges 75 18 may be disposed a valve seat 20 having a valve 21 of any desired construction. Where reducer couplings are employed, the valve seat 20 will be held in position by these 80 couplings.

In order that the cylinder 13 may accommodate a wooden suction pipe such as illustrated in Figure 5, the lower end of the bore is tapered, as indicated at 22, for coaction with the tapered upper end 23 of the 85 wooden suction pipe, the cylinder being forced down upon the suction pipe. If desired, the collar 17 may be employed with the wooden suction pipe to prevent spreading of the lower end of the cylinder when 90 the suction pipe swells as it becomes saturated with liquid. Within the cylinder is disposed a piston 24 provided with ring grooves 25 in which are seated packing rings 26 similar to those employed on the pistons 95 of internal combustion engines. The piston 24 is provided with a central opening affording at its upper end a valve seat 27 for coaction with a valve 28. The lower surface of the piston is perfectly flat and plain in 100 order that the same may be employed for engaging a trip 29 formed on the valve 21 to open this valve and drain the cylinder 13 of water. To the upper end of the piston is secured a cage 30 which is secured to the 105 pump rod 31 in the usual manner.

The form of piston just described is preferably employed for pumping, oil, gas and the like. For the pumping of water I prefer to employ a piston such as disclosed in Figure 6. This piston comprises an annular member 32 of slightly less diameter than the 110

cylinder within which it is employed and having extending upwardly from the upper face thereof a yoke 32^a provided with an opening 33 for the reception of the pump rod 31. The annular member 32 coacts with a second annular member 34 to maintain therebetween a cup leather 35, the annular members being clamped together upon the leather 35 by means of securing elements 36 and 37 10 extending through the annular members 32 and 34. The securing member 37 likewise forms a fastening means for a clamping plate 38 which clamps against the upper surface of the annular member 32, a valve 15 leather 39 extending completely across the opening 32^b of the annular member 32. To the upper surface of the valve leather 39 a plate 40 is secured, as at 41, this plate being of slightly greater size than the opening 20 32^b and having the edge thereof next adjacent the clamping plate 38 spaced therefrom, as indicated at 42, in order that the exposed section of the valve leather 39 may act as a hinge. It is pointed out that the 25 plate 40 greatly rigidifies the valve leather and assists in the proper setting thereof.

It is to be noted that the construction of the pump cylinder is such that a great amount of room is provided for the passage 30 of fluid through the valves. It will furthermore be obvious that by employing a piston and cylinder of the construction hereinbe-

fore set forth in conjunction with the force pump structure, the device may be used as a lift pump through a distance of approximately thirty-two feet and subsequently employed as a force pump to elevate the water the remaining distance. In addition, a cylinder constructed as shown may be employed either at the end of a suction lift or submerged as desired. Many changes being possible in the shape, size and arrangement of the various parts hereinbefore set forth, I do not limit myself thereto except as hereinafter claimed. 45

I claim:—

1. In a pump, a cylinder having an open lower end, the bore of the cylinder at the lower end thereof being tapered to permit the insertion therein of a wooden suction 50 pipe, said lower end of said cylinder being provided with screw-threads adapted for the reception of a coupling member whereby a metal suction pipe may be attached to the cylinder. 55

2. A pump cylinder having an open lower end, the bore of the cylinder at the lower end being tapered, the wall of the cylinder being provided interiorly and exteriorly with screw-threads as and for the purpose 60 set forth.

In testimony whereof I hereunto affix my signature.

LOUIS FRANK PONTBRIAND.
